US00D940720S

(12) **United States Design Patent** (10) **Patent No.:** **US D940,720 S**
(45) **Date of Patent:** **** Jan. 11, 2022**

(54) **MIC BLOCK WITH LEASH HOLE**

(71) Applicant: **C-SLIDE HOLDINGS, LLC**, Lehi, UT (US)

(72) Inventor: **Ronald Glen Gustaveson, II**, Lehi, UT (US)

(73) Assignee: **C-SLIDE HOLDINGS, LLC**, Lehi, UT (US)

(**) Term: **15 Years**

(21) Appl. No.: **29/661,940**

(22) Filed: **Aug. 31, 2018**

Related U.S. Application Data

(63) Continuation-in-part of application No. 15/752,652, filed on Feb. 14, 2018, now Pat. No. 10,374,349.

(57) **CLAIM**

The ornamental design for a mic block with leash hole, as shown and described.

DESCRIPTION

FIG. 1 is a front top right perspective view of the mic block with leash hole;

FIG. 2 is a rear top left perspective view thereof;

FIG. 3 is a front elevational view thereof;

FIG. 4 is a left elevation view thereof;

FIG. 5 is a right elevation view thereof;

FIG. 6 is a rear elevation view thereof;

FIG. 7 is a top plan view thereof;

FIG. 8 is a bottom plan view thereof;

FIG. 9 is a rear elevation view of the mic block with leash hole having a leash threaded therethrough during use; and, FIG. 10 is a perspective view of the mic block with leash hole having a leash threaded therethrough during use.

The broken lines shown in the drawings are included to illustrate environment portions of the mic block with leash that form no part of the claimed design.

1 Claim, 3 Drawing Sheets
